DOLLHOUSE

Robert E. Ralston, Seattle, Wash.

Application September 23, 1949, Serial No. 5,144

Term of patent 14 years

(Cl. D34—15)

To all whom it may concern:

Be it known that I, Robert E. Ralston, a citizen of the United States, residing at Seattle, in the county of King and State of Washington, have invented a new, original, and ornamental Design for a Dollhouse, of which the following is a specification, reference being had to the accompanying drawings, forming a part hereof.

Fig. 1 is a birdseye perspective view of a dollhouse, showing my new design;

Fig. 2 is a view similar to Fig. 1 except that the device in Fig. 2 has been rotated in a clockwise direction approximately 100° over the position shown in Fig. 1;

Fig. 3 is a view similar to Fig. 1 except that the device in Fig. 3 has been rotated in a clockwise direction approximately 180° over the position shown in Fig. 1; and

Fig. 4 is a view similar to Fig. 1 except that the device in Fig. 4 has been rotated in a clockwise direction approximately 260° over the position shown in Fig. 1.

I claim:

The ornamental design for a dollhouse, as shown.

ROBERT E. RALSTON.
